UNITED STATES PATENT OFFICE.

LEE J. SMITH, OF. WANNEE, FLORIDA.

ROLLER-SUPPORT FOR MOVABLE DOORS.

No. 845,134.

Specification of Letters Patent.

Patented Feb. 26, 1907.

Application filed May 14, 1906. Serial No. 316,838.

To all whom it may concern:

Be it known that I, LEE J. SMITH, a citizen of the United States, residing at Wanee, in the county of Alachua and State of Florida, have invented certain new and useful Improvements in Roller-Supports for Movable Doors, of which the following is a specification.

This invention relates to brackets for freight-car and other doors.

One object of the invention is to provide a bracket adapted to movably support and guide doors of various description.

Another object resides in the provision of a bracket carrying a roller and constructed and arranged to support and guide freight-car doors effectively, the roller being so arranged in the bracket as to prevent grain or other material becoming clogged between the roller and bracket.

With the above and other objects in view the present invention consists in the combination and arrangement of parts hereinafter referred to, shown in the accompanying drawings, and particularly pointed out in the appended claim.

In the drawings, Figure 1 is a side elevation of a portion of a freight-car door arranged with relation to one of my improved brackets. Fig. 2 is a longitudinal section view of the invention, a portion of the door and the roller being shown in elevation; and Fig. 3 is a transverse sectional view of the invention, the roller being shown in elevation.

Referring now more particularly to the accompanying drawings, there is shown a freight-car or other door 1, adapted to be slidably supported upon one or more rollers 2, and guided in its movement by a bracket 3, designed to support the roller.

The bracket consists of a securing-plate 4 and a guiding-plate 5, disposed in spaced relation to each other by the spaced connecting-webs 6, one end of each web being enlarged with its inner face tapered to correspond with the curvature of the periphery of

the roller 2, and thereby form the oppositely-disposed lips 7, overhanging the roller to prevent clogging of grain or other material between the webs and the roller. By reason of these lips 7 the roller cannot be placed within the bracket or removed therefrom by way of the lips, because the opening 8 at this end of the bracket is less than the diameter of the roller. However, the opposite end of the opening 8 is not contracted, but of such size as to permit of the insertion or removal of the roller.

The roller 2 may be mounted upon any suitable shaft; but in the drawings I illustrate a shaft 9, having a head 10, adapted to lie against the outer face of the guide-plate when the opposite screw-threaded end 11 is fitted in the screw-threaded perforation 12 in the securing-plate 4. As just intimated, the roller-shaft may be of any other form, and it may be otherwise supported, but preferably arranged so as to permit part of the roller to lie above the upper edge of the securing-plate 4 to engage the under edge of the door 1.

The securing-plate 4 is provided with perforations 13, through which suitable fastenings (not shown) may be passed to secure the bracket to a car (not shown) immediately beneath the door, and as the latter is moved over the roller the flange 14 of the guiding-plate presents its inner face to the outer of the door and properly guides the latter.

What is claimed is—

A bracket comprising a securing-plate and a guiding-plate connected by spaced webs to form an opening, a guiding-plate extending above the securing-plate and a roller mounted in said opening, the upper inner edges of said webs overhanging the roller.

In testimony whereof I have signed my name to this specification in the presence of two subscribing witnesses.

LEE J. SMITH.
